UNITED STATES PATENT OFFICE.

WILLIAM M. SHEEHAN, OF ST. LOUIS, MISSOURI, ASSIGNOR TO CAST STEEL LOCOMOTIVE ASH PAN COMPANY, OF ST. LOUIS, MISSOURI, A CORPORATION OF DELAWARE.

LOCOMOTIVE ASH PAN.

Application filed February 4, 1921. Serial No. 442,487.

To all whom it may concern:

Be it known that I, WILLIAM M. SHEEHAN, a citizen of the United States, residing at St. Louis, Missouri, have invented a certain new and useful Improvement in Locomotive Ash Pans, of which the following is a full, clear, and exact description, such as will enable others skilled in the art to which it appertains to make and use the same, reference being had to the accompanying drawings, forming a part of this specification.

This invention relates to new and useful improvements in locomotive ash pans, the objects being to provide a locomotive ash pan in which the door supporting means and the door operating mechanism are both supported on said ash pan, thereby insuring a uniform expansion of said supporting means and said door operating mechanism so that the door is maintained in proper position at all times.

Other objects of the invention are to construct a locomotive ash pan, so that the operating shaft of the door operating mechanism is located within said ash pan, thereby permitting an increase in its capacity; and to provide a housing within said ash pan enclosing said shaft and having an air chamber so that air can circulate around said shaft and protect it from the excessive heat generated in said ash pan by the ashes contained therein.

Further objects of the invention are to provide the lower front end of the door opening with a depending transverse flange which, when the door is partly opened, will act as an air deflector and prevent currents of air jetting into said ash pan and igniting the contents thereof.

With the foregoing and other objects in view, my invention consists in certain novel features of construction and arrangement of parts, hereinafter more fully described and claimed, and illustrated in the accompanying drawings, in which—

Figure 1 is a side elevation of the ash pan.

Figure 2 is a front elevation of the same.

Figure 3 is a fragmentary sectional view taken on the line 3—3 of Figure 1.

Figure 4 is a plan view of the front end of the ash pan.

Figure 5 is a longitudinal cross section taken through the lower portion of the ash pan.

Referring by numerals to the accompanying drawings, 10 designates a hopper attached in the usual manner to a locomotive fire box 11 shown in dotted lines in Figure 1. Depending from hopper 10 and supported thereon is an ash pan 12 having side walls 13, front end wall 14 and a rear end wall 15. This rear end wall consists of a forwardly and downwardly inclined portion 15^a and a more steeply inclined portion 15^b. The wall portion 15^a is located a sufficient distance above the axle 16 of a locomotive trailer truck to provide the necessary clearance for a booster mechanism which, when a locomotive is so equipped, cooperates with axle 16. The downward wall portion 15^b is located the proper distance in front of axle 16 to provide the necessary clearance between said wall portion and said axle and to provide additional clearance for a swinging door 18 which, when in open position, is swung rearwardly of said wall portion 15^b, as shown in dotted lines in Figure 1. Door 18 is arranged to rest against the lower edges of side walls 13, front wall 14, and rear end wall 15, so as to form the bottom of ash pan 12, and is swingingly supported on said ash pan by links 19 pivotally mounted in brackets 20 which are formed on side walls 13 and the lower ends of arms 19 are pivotally connected at 21 to depending flanges 18^a of door 18.

A shaft 22 passes transversely through the interior of the ash pan 12 and has its ends which project outwardly from side walls 13 journaled in bearings 23 which are fixed to said side walls and are located in front of brackets 20. Arms 24 are fixed to the ends of shaft 22 and pivotally connected to the free ends of said arms are the outer ends of connecting links 25, their opposite ends being pivotally connected by means of bolts or pins 26 to flanges 18^a of door 18. The rear edge of door 18 extends beyond the edge of wall portion 15^b and is turned upwardly to provide a flange which when the door is partly opened prevents air from entering the ash pan past the lower edge of wall 15^b.

The front end wall 14 has an inwardly extending flange 14^a, the upper wall of which is inclined to permit the ashes to pass downwardly and the front edge of door 18 is designed to rest against flange 14^a.

when said door is in closed position. Intersecting ribs 13^a are diagonally disposed on the inner faces of side walls 13 and reinforce and prevent buckling or warping of 5 said side walls by the heat from the ashes contained therein.

A depending transverse flange 27 is formed on the front end wall 14. This flange is located in front of the door opening of said ash pan and extends downwardly 10 below said opening a sufficient distance to act as an air deflector which, when the door is partly opened, will prevent the air from jetting or rushing into the ash pan and 15 causing combustion of its contents.

One end of shaft 22 is provided with a hand-operated arm 28 whereby by operating 20 said arm in the proper direction, shaft 22 is rotated, moving arms 24 rearwardly and 25 causing door 18 through its connection 25 with arms 24 to swing on its pivotal supports 19 and assume the position shown in dotted lines in Figure 1. By reversely rotating 30 shaft 22 by means of arm 28, arms 24 are brought forward, thereby causing door 18 to move against the lower edges of side walls 13, front end wall 14 and rear end wall 15, and thereby close the lower end of ash pan 12. The shaft 22 passes through the interior 35 of the ash pan and in order to prevent distortion of said shaft by the heat generated in said ash pan by the ashes contained therein, a tubular housing 29 extends through 40 said ash pan and encloses shaft 22. The ends 45 of housing 29 terminate and are supported in side walls 13 and are open to the atmosphere so that air can circulate through said housing. The tubular housing 29 is of sufficient size to provide an air chamber between 50 said housing and shaft 22, the ends of said housing being open, and the air entering said housing and circulating around said shaft lowers the temperature in said housing and prevents the distortion of shaft 22 by 55 the heat in said ash pan.

By mounting the door supporting means and the door operating mechanism on the ash pan proper, the expansion of said supporting means and said operating mechanism 50 (which expansion is due to the heat caused by the ashes in the ash pan) is uniform so that said door operating mechanism and door supporting means always maintain the proper working relation with the door and with each other, thereby insuring effective working conditions of said door.

When either the door supporting means or the door operating mechanism is supported from any other part of the locomotive 60 than the ash pan, the expansion of the various parts is unequal due to the fact that parts supported on the ash pan are subjected to greater expansion than the parts not supported on the ash pan so that the proper working relation between said parts is sup-

ported is destroyed causing inefficient closure of the ash pan or difficulty in operating the door operating mechanism.

The provision of a tubular housing extending transversely within said ash pan 70 permits the location of the operating shaft of the door operating mechanism within said ash pan without the danger of distortion of said shaft by the heat from the ashes. The capacity of the ash pan is thereby increased 75 since the shaft being located within the ash pan and the door supporting means and the door operating mechanism being supported on the side walls thereof, the front portion of said ash pan can be extended forward as far as practicable. 80

An ash pan constructed according to my design is of simple and strong construction 85 and provides uniform expansion for its door supporting and operating parts, thereby insuring the proper closing of the ash pan at all times.

While I have shown and described the invention with hand-operated means, it is obvious that the door operating mechanism 90 can be operated mechanically.

Various changes in the form, proportion and details of construction may be resorted to, without departing from the spirit of the invention, the scope of which is set forth in 95 the appended claims.

I claim:

1. A locomotive ash pan provided in its bottom with a discharge opening, links 100 swingingly suspended from the side walls of said ash pan, a door for said discharge opening pivotally supported partially by the lower ends of said links, a rock shaft extending transversely through said ash pan, a housing spaced from said shaft and enclosing an insulating space around said shaft, rock arms fixed to the ends of said rock shaft, links pivotally connected at their lower ends to said door and at their upper ends to said rock arms, and a manually operable arm fixed to one end of said rock shaft. 105

2. A locomotive ash pan provided in its bottom with a discharge opening, a door for closing said opening, a plurality of links 115 arranged in pairs for supporting said door, one pair of said links being pivotally suspended from the side walls of said ash pan and pivotally connected at their lower ends to said door, and the other pair of links being pivotally connected at their lower ends to said door suitable distance from the pivotal connections of the first pair of links, a rock shaft transversely arranged in said ash pan, a housing spaced from said shaft 120 and enclosing an insulating air space therearound, rock arms fixed to the ends of said shaft and pivotally connected at their ends to the free ends of the last mentioned pair of links whereby when said shaft is rocked, 125 130

said door is actuated on the axes of the pivotal connections of the first pair of links.

3. A locomotive ash pan provided in its bottom with a discharge opening, a closure member therefor, means for swingingly supporting said member in position, a rock shaft arranged within said ash pan, operating connections between said closure member and said rock shaft, and a housing in said ash pan having its ends supported by the side walls of the ash pan, said housing enclosing said shaft and forming an insulating space around said shaft.

4. A locomotive ash pan provided with a sloping bottom and having a discharge opening formed therein, a door for closing said opening, means pivotally suspended from said ash pan and pivotally supporting said door, bearings carried by the side walls of the ash pan and spaced therefrom, a rock shaft extending transversely through said ash pan and having its ends journaled in said bearings, a housing for said shaft arranged in and supported by said ash pan and spaced from said shaft whereby said shaft is insulated from the contents of the ash pan and air is allowed to circulate through said housing and cool said shaft, rock arms fixed to the ends of said shaft, and links pivotally connected at their ends to said arms and said door.

5. A locomotive ash pan provided with a door adapted to close the lower end thereof and supported thereon, an operable shaft journaled in said ash pan and extending through the interior thereof, means operatively connecting said shaft with said door,

and means in said ash pan enclosing said shaft and provided with an air chamber through which cooling medium may circulate around said shaft.

6. A locomotive ash pan provided with an inclined bottom having a discharge opening, a door for closing said discharge opening, an open ended tubular member supported on said ash pan and extending therethrough, a rock shaft supported by said ash pan and arranged within said tubular member, said tubular member being spaced from said shaft to provide heat insulating air space around said shaft, an arm fixed to each end of said shaft, links arranged in pairs for operatively supporting said door, one pair of links being pivotally mounted on said ash pan and the other being pivotally connected to said arms, and an operating arm fixed to one end of said shaft.

7. A locomotive ash pan provided with an open-ended tubular housing fixed in the side walls thereof and extending transversely through the interior of said ash pan, a shaft located within said housing and journaled in bearings carried by said ash pan, there being formed an air chamber between said housing and said shaft whereby air can circulate through the open ends of said housing and around said shaft, a door adapted to close the lower end of said ash pan and operatively connected to said shaft, and means for operating said shaft.

In testimony whereof I hereunto affix my signature this 1st day of February, 1921.

WILLIAM M. SHEEHAN.
